US0D1018064S

(12) **United States Design Patent** (10) **Patent No.:** **US D1,018,064 S**
(45) **Date of Patent:** **** Mar. 19, 2024**

(54) **TOOTHBRUSH HEAD**

(71) Applicant: **EcoLife Innovations LLC**, Cape Coral, FL (US)

(72) Inventor: **Tilong Lu**, Yangzhou (CN)

(73) Assignee: **EcoLife Innovations LLC**, Cape Coral, FL (US)

(**) Term: **15 Years**

(21) Appl. No.: **29/789,408**

(22) Filed: **Sep. 21, 2021**

(51) LOC (14) Cl. **04-02**
U.S. Cl.

USPC **D4/101**

(58) **Field of Classification Search**
